PUMP AND MOTOR THEREFOR

Arthur E. McFarland, Houston, Tex., assignor to
McFarland Manufacturing Corporation, Houston, Tex., a corporation of Texas

Application December 21, 1948, Serial No. 66,435

17 Claims. (Cl. 121—150)

1

This invention relates to a pump and a motor therefor and refers more particularly to devices adaptable for use in pumping flowable material in predetermined increments and at predetermined time intervals.

Devices of this invention have many uses and by way of example but not by way of limitation, the device may be employed for injecting chemicals known as emulsion breakers into well fluids containing crude petroleum as it is produced from oil wells. These chemicals break up the water oil emulsions often present in well fluids. It is old practice to inject emulsion breaking chemicals in to the well fluids but difficulty has been encountered in accomplishing this inexpensively and yet in such manner as to obtain substantially uniform distribution of the treating chemicals in the produced well fluids. The motor may be used for any purpose where it is desired to reciprocate a rod.

An object of this invention is to provide a simple, rugged, low-cost device that will positively pump a flowable material at predetermined time intervals and in predetermined amounts or increments.

Another object is to provide a device of the character described which may be motivated by fluid under pressure and which may be readily and easily regulated to change the time interval between successive charges or increments of flowable material.

A further object is to provide a device of the character described which may be readily and easily adjusted to change the quantum of each increment of flowable material that is discharged into another fluid.

Still another object is to provide a motor for chemical injectors or the like in which the length of the actuating stroke is automatically varied in response to the temperature conditions under which the device is operating.

A still further object is to provide a motor for devices of the character described which is simple, rugged, inexpensive and yet positive in its action.

Yet another object is to provide a motor for devices of the character described wherein the time interval of operation may be readily and easily adjusted.

Yet a further object is to provide a motor for devices of the character described in which the length of the stroke of the drive part of the motor may be readily and easily adjusted.

Other and further objects of this invention will appear from the description.

2

In the accompanying drawings which form a part of the instant specification, are to be read in conjunction therewith, and wherein like reference numerals are used to indicate like parts in the various views:

Fig. 1 is a top plan view, with parts broken away for illustrative purposes, of a device embodying this invention; and

Fig. 2 is a fragmentary view upon an enlarged scale showing in cross-section the power generating portion of the device shown in Fig. 1.

The device of this invention may be considered as a pump having a motor for intermittently but regularly operating the pump. The motor itself serves as its own timing unit.

Referring to the drawings, a pump head is shown at 5 having a pump chamber 6 therein, which may be an axial bore in which the pump member 7 is adapted to reciprocate to vary the capacity of chamber 6. The pump member 7 preferably is provided with a sliding seal between the wall of the bore and the pump head. A satisfactory seal may be provided by a plurality of conventional O-rings 8 fitting in peripheral grooves encircling the pump member 7.

The pump chamber 6 is provided with inlet and discharge ports 9 and 10 respectively. Each of these ports should be controlled by suitable check valves. A satisfactory check valve comprises a tubular member 11 having an axial bore therethrough with an interior seat surface 12 against which ball valve 13 seats. Spring 14 urges the ball against the seat to prevent back flow of fluid through the tubular part.

This valve arrangement may be connected in the inlet port 9 by fitting 15 and have its other end connected to a pipe 16 which communicates with a reservoir for flowable material to be pumped, which isn't shown in the drawings. The same arrangement may be employed for controlling the discharge of the pump head in which case the fitting 15 is connected to the opposite end of part 11 and threaded in port 10. The discharge pipe 17 is connected to the other end of part 11 and may communicate with any fluid container also omitted from the drawings. With this arrangement, it is believed apparent that reciprocation of pump member or plunger 7 will serve to alternately draw material through pipe 16 into chamber 6 and then to discharge the material through pipe 17 into the fluid receptacle. The motor for reciprocating the pump member should, for chemical injecting purposes, operate intermittently at predetermined time intervals and with a predetermined length of stroke.

The actuating mechanism for accomplishing this, in accordance with this invention, is detailed in Fig. 2 of the drawings.

All the actuating mechanism may be housed in a compact housing as a unit made up of a mandrel 18, a sleeve 19 and a nipple part 20, with a pressure chamber 21 secured thereto and preferably welded thereto. Sleeve 19 preferably has an easily broken threaded connection with mandrel 18, which in use may be separated by hand. Nipple 20 is also threadedly connected with sleeve 19 and a seal is provided between these two parts preferably in the form of an O-ring 22 in a peripheral groove carried by the nipple. A suitable latch 23 prevents accidental breaking of this threaded connection and provides a manually operable, accessible means for controlling the length of the stroke for the end of the nipple limits movement of the power driven part of the motor as will hereinafter more fully appear.

The entire power unit housed in the parts just described may be secured in axial alignment with the pump head by a spacer sleeve 24 secured between confronting ends of pump head 5 and mandrel 18 by suitable studs 25.

The power mechanism may be considered generally as including a pressure responsive member urged in a direction to produce a suction stroke by a yieldable force. The pressure responsive member is urged in the opposite direction intermittently by a greater force accomplished by the intermittent pressurizing of the chamber in which the pressure responsive member resides by pressure fluid trapped within the pressure dome. The pressure dome is supplied with a pressure fluid at a predetermined rate and when the pressure within the dome reaches a predetermined value, a relief valve mechanism establishes communication between the pressure dome and the chamber for the pressure responsive member. Thus, the time interval of operation depends upon the rate of flow of pressure fluid into the pressure dome. The pressure dome and the chamber for the pressure responsive member are both vented at the end of the power stroke and the pressure responsive member is returned to position for a successive power stroke by the yieldable force.

The foregoing is preferably accomplished by providing first and second cylinders within the mandrel and sleeve 19 in axial alignment as provided by bores or cylinders 26 and 27. The pressure responsive member resides in cylinder 27 and may be a piston member 28. This piston is threaded to a plunger 29 and may have a peripheral groove for receiving a seal element 30, preferably a split ring formed of rubber, neoprene, leather or the like. It is desirable that the piston 28 have a substantial seal within cylinder 27 but that this seal not be absolute in order to facilitate proper venting of the power side of cylinder 27 and the dome.

The pressure dome is provided by the interiors of pressure chamber 21 and nipple 20. This pressure dome opens into the cylinder 27 at the flared left hand end of nipple 20 as viewed in Fig. 2. In order to close this opening with the piston in its extreme right hand position as viewed in Fig. 2, a part 31 is provided. Preferably a seal is provided between part 31 and the flared end of the nipple which may be in the form of an O-ring 32 carried by part 31 and adapted to engage the flared portion of nipple 20.

This part 31 and seal element 32 may be considered as a pressure responsive member having

an effective area equal to the area enclosed within the seat. This effective area is exposed to pressure within the pressure dome and as this force or pressure builds up, the force tending to drive the pressure responsive member and plunger on the power stroke increases until it is able to overcome the yieldable force which urges the pressure responsive member and plunger in the opposing or seating direction. Immediately upon overcoming this yieldable seating force, the opening between the chamber or cylinder 27 and the pressure dome becomes unobstructed and pressure fluid is supplied to cylinder 27 upon the power side of piston 28. This pressure will be substantially the pressure of the dome and due to the larger area of the effective pressure face of piston 28, the force driving the piston and plunger on its power stroke will be greatly increased to positively actuate the pump member 7. The connection of the pump member with the pressure responsive member will be herein-after more fully detailed.

Cylinder 27 preferably is provided with two vent ports. Vent port 33 is always open to provide for venting of the cylinder 27 on the side of piston 28 remote from its pressure face. A large port 34 is provided in the wall of the cylinder in such position as to be uncovered by piston 28 as it approaches its full or extreme power stroke position. Port 34 preferably is large so as to quickly exhaust the pressure fluid within the power side or portion of cylinder 27 and the dome. With the pressure dome thus released, the yieldable force urging the pressure responsive member 28 towards its right hand position moves the piston into the position shown in Fig. 2.

The means for providing the yieldable force opposing the power stroke of piston 28 may be any suitable yieldable means, as for example a spring, but preferably and conveniently may be a pneumatic means as provided by cylinder 26. The pressure responsive member within this cylinder is the plunger 29 which is mounted for sliding reciprocation within cylinder 26. A sliding seal may be provided between the plunger and mandrel 18 as, for instance, by an O-ring 35 in a peripheral groove encircling plunger 29. Cylinder 26 may be pressurized from any suitable source of fluid pressure, but the regularity of operation of the device is greatly improved by supplying the cylinder with a regulated pressure. Opening 36 in the mandrel wall carries a fitting 37 which may be a conduit leading from a suitable source of pressure fluid supply as indicated by regulator 38.

The end of plunger 29 exposed interiorly of cylinder 26 is in effect a pressure face and the force of the pressure within this cylinder acting against the end of the plunger, drives or urges the plunger on the suction stroke.

The actuating connection between the pressure responsive member 28 and the pump member 7 includes the plunger 29 to which the end of rod or pump member 7 is secured. Preferably this connection is yieldable on the power stroke. A yieldable connection is shown in the drawings in the form of a recess 39 in the end of plunger 29. The threaded end of rod 7 is secured in this recess by nut 40 threaded in the recess and nut 41 threaded to rod 7 interiorly of the recess. Spring 42 abuts against the end of the recess and the inner side of nut 41 resiliently urging the plunger toward its power stroke.

Rod 7 extends through the left hand end of mandrel 18, as viewed in Fig. 2, and a seal is pro-

vided between the rod and the mandrel. In the form shown, the O-ring 43 effects this seal and resides in a peripheral grooved formed in rod 7.

Referring now to the pressurization of the pressure dome, that is, the interiors of nipple 20 and pressure chamber 21, this is desirably accomplished by providing a restricted flow bypass between cylinder 26 and the interior of the pressure dome. By this expedient, a single source of pressure may be employed to provide the forces for reciprocating the pressure responsive member in both directions. It is also desirable that this bypass be located interiorly of the housing for the device to prevent children, trespassers or the like from tampering therewith and to reduce the likelihood of accidental breakage of the bypass. This may be conveniently provided by forming an opening or passage 44 extending axially of plunger 29. This passage communicates with the interior of cylinder 26 by radial ports communicating between recess 39 and the exterior of plunger 29. Also the portion of plunger 29 immediately surrounding the recess 39 may be of somewhat reduced diameter to provide for free flow of fluid into the recess. The right hand end of passage 44 communicates with the interior of the pressure dome and a restriction is provided in the passage to effect a predetermined rate of charging of pressure fluid into the pressure dome. This restriction preferably is of an adjustable nature.

A suitable adjustable restriction for the flow of fluid through passage 44 includes a recess in the right hand end of plunger 29 in which is threaded a sleeve 46. Sleeve 46 is notched at both ends, the notch on the exterior of the sleeve accommodating a tool to facilitate rotation of the sleeve to adjust its position axially in the recess and the notch on the interior end of the sleeve providing for flow of fluid into the interior of the sleeve past a ball valve member 47. By adjusting the axial position of sleeve 46, the amount of opening provided between the right hand end of passage 44 and ball valve 47 may be adjusted to predetermine the rate of flow therethrough. Sleeve 46 may be secured in a set position by manipulation of lock nut 48. A suitable soft gasket 49 seals the joint between lock nut 48, the reduced diameter portion of plunger 29 and the inner periphery of part 31 to prevent leakage of pressure fluid from the pressure dome to the pressure side of piston 28.

To limit the movement of piston 28 in a power stroke direction, a wear washer and cushion, preferably fabricated of a cushioning material such as leather or the like, shown at 50, is provided encircling the plunger 29 intermediate piston 28 and the end of mandrel 18. In order that the length of the power stroke might be adjusted, a wedge element 51 is mounted to extend into vent opening 33 having its flat or straight surface abutting the end of mandrel 18. The inclined or wedge surface of the stop will be struck by washer 50 on the power stroke and by advancing the wedge inwardly or outwardly of the opening, the length of the stroke may be adjusted.

It is preferable that the stroke be adjustable thermostatically in response to the temperature of the material being pumped. This is true because the temperature of the flowable material, especially where viscous liquids are involved, determines the viscosity of the material and the more viscous the material, the longer the stroke should be in order to properly pump a full in-

crement as desired. For this reason, the stop 51 is secured to a coiled heat sensitive element 52 retained in housing 53 secured to the exterior of sleeve 19. As the temperature exteriorly of the motor increases, element 52 expands, forcing block or stop 51 further inwardly of the opening 33. Obviously, cooling of the atmosphere will cause a slight retraction of the stop. Assuming that the temperature of the material being pumped is substantially atmospheric, as where retained in a reservoir exposed to the atmosphere, the length of the stroke will be a function of the temperature of the material and therefore, the viscosity thereof. It is contemplated that this element 52 could be exposed directly to the material being pumped. The main adjustment for the length of stroke is accomplished manually by adjusting the position of nipple 20 relative to sleeve 19 thereby determining the limit of movement of piston 28 in cylinder 27 in the right hand direction as viewed in Fig. 2.

It is believed that the operation of the device of this invention is apparent from the foregoing description. The pressure fluid is continuously supplied to the interior of mandrel 18 at a constant pressure. The fluid bleeds through passage 44 past valve 47 at a rate determined by the position of sleeve 46 to pressurize the pressure dome at a predetermined rate. The force of the pressure within cylinder 26, acting against plunger 29, urges the plunger and piston 28 to its right hand position with seal element 32 and part 34 sealing off the opening between the pressure dome and the interior of cylinder 27. This condition will prevail until the pressure within the dome builds up to a degree that the resultant force of the pressure across seal 32 is greater than the force of the pressure within cylinder 26 against plunger 29. When this occurs, the seal 32 will become ineffective and the portion of cylinder 27 on the pressure dome or power side of piston 28 will be energized to drive the piston to the left as shown in the drawings. As the piston approaches its extreme left hand position, vent port 34 is uncovered, relieving the pressure within the pressure dome and cylinder 27. With this pressure relieved, the pressure within cylinder 26 drives the piston to the right, as shown in the drawings, and the pressure dome is again sealed off.

The time interval of operation of the motor is adjustable by manipulating sleeve 46. To accomplish this, it is necessary to break the union between mandrel 18 and sleeve 19 and for this reason, this union is usually made up only as a finger tight joint. When this union is broken, sleeve 19, nipple 20 and pressure chamber 21 are removed exposing piston 28. Inasmuch as the piston does not have an absolute seal with cylinder 27, these parts are readily removed to provide access to sleeve 46. Practically the only wearing part in the entire motor is the seal element 32 and access to this element to replace it may be had in the same fashion. When proper adjustment of ball valve 47 has been made or seal 32 replaced, the portion of the housing made up of the nipple, sleeve and pressure chamber are restored to position and again a finger tight joint is preferred in order to allow easy access for future adjustment or replacement of the seal element.

There has been provided an automatic adjustment of the stroke of the pump member responsive to temperature changes exteriorly of the motor in the form of the thermostatic element

52 which governs the position of stop 51. The stop 51 is abutted by washer 50 upon the end of the power stroke of piston 28 and the position of the stop, in a radial sense, determines the length of the stroke within limits.

From the foregoing, it will be seen that this invention is one well adapted to attain all of the ends and objects hereinabove set forth, together with other advantages which are obvious and which are inherent to the structure.

It will be understood that certain features and sub-combinations are of utility and may be employed without reference to other features and sub-combinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

Having described my invention, I claim:

1. A motor adaptable for connection to a rod for intermittently reciprocating same, comprising a housing, a pressure responsive member in the housing connectable with a rod, said member dividing the interior thereof into a plurality of compartments, one of which is a variable capacity pressure compartment, vent means actuated by movement of said member to vent said pressure compartment at the limit of the power stroke, a means yieldingly urging the pressure responsive member in a direction opposed to the power stroke, a pressure dome with a fitting therefor through which a pressure fluid may be supplied to the dome at a predetermined rate, and means for establishing communication between the pressure compartment and the pressure dome when the pressure within the dome reaches a predetermined value.

2. A motor adaptable for connection to a rod for intermittently reciprocating same comprising a housing, a pressure responsive member in the housing connectable with a rod, said member dividing the interior thereof into a plurality of compartments, one of which is a variable capacity pressure compartment, vent means actuated by movement of said member to vent said pressure compartment at the limit of the pressure responsive member's power stroke, a pressure means urging the pressure responsive member in a direction opposed to the power stroke, a pressure dome with a fitting therefor to which a pressure fluid may be supplied to the dome at a predetermined rate, and means for establishing communication between the pressure compartment and the pressure dome when the pressure within the dome reaches a predetermined value.

3. A motor adaptable for connection to a rod for intermittently reciprocating same comprising a housing, a pressure responsive member in the housing connectable with a rod, said member dividing the interior thereof into a plurality of compartments, one of which is a variable capacity pressure compartment, vent means actuated by movement of said member to vent said pressure compartment at the limit of the pressure responsive member's power stroke, a pressure means urging the pressure responsive member in a direction opposed to the power stroke, a pressure dome with a fitting therefor through which a pressure fluid may be supplied to the dome at a predetermined rate, a passage communicating between the pressure compartment and pressure dome, a part carried by the pressure responsive member

adapted to seat in the passage to close same with the pressure responsive member in position to commence its power stroke and to move therefrom to open the passage when the pressure in the dome reaches a predetermined value due to the force of the pressure acting against said part.

4. A motor adaptable for connection to a rod for intermittently reciprocating same comprising a cylinder, a piston mounted for reciprocal movement in the cylinder, vent means in the cylinder adapted to relieve the pressure in the power chamber of the cylinder when the piston approaches the end of its power stroke, a pressure dome adapted to be supplied with a pressure fluid at a predetermined rate, an opening between the pressure dome and the interior of the cylinder upon the power side of the piston, a relief valve controlling the opening adapted to open upon occurrence of a predetermined pressure within the pressure dome, and yieldable means urging the piston toward its position at the commencement of the power stroke.

5. A motor adaptable for connection to a rod for intermittently reciprocating same comprising a cylinder, with spaced vent and pressure supply openings, a piston mounted within the cylinder for reciprocal movement between the pressure supply opening and vent and adapted to move to a position on termination of the power stroke to place the vent opening in communication with the cylinder upon the power side of the piston, a part carried by the piston and having a lesser cross-sectional area than the effective pressure face of the piston, said part adapted to seat in the pressure supply opening with the piston in extreme position in the cylinder at the commencement of the power stroke, and yieldable means urging the piston in a direction to close the pressure supply opening.

6. A motor adaptable for connection to a rod for intermittently reciprocating same comprising a cylinder with spaced vent and pressure supply openings, a piston mounted within the cylinder for reciprocal movement between the pressure supply opening and vent and adapted to move to a position on termination of the power stroke to place the vent opening in communication with the cylinder upon the power side of the piston, a part carried by the piston and having a lesser cross-sectional area than the effective pressure face of the piston, said part adapted to seat in the pressure supply opening with the piston in extreme position in the cylinder at the commencement of the power stroke, yieldable means urging the piston in a direction to close the pressure supply opening, a pressure dome communicating with said pressure supply opening, and a fitting for the dome through which the dome may be pressurized at a predetermined rate.

7. A motor adapted to have an operating connection with a rod for reciprocating same intermittently at regular intervals comprising a housing with a pressure chamber therein, a plunger in the chamber having a pressure face exposed to one portion of the interior of the chamber to urge the plunger in one direction, a fitting for supplying pressure fluid to this portion of the chamber, two other differential pressure faces carried by the plunger and adapted when exposed to pressure in another portion of the chamber to urge the plunger in the opposite direction, a pressure dome having an opening into that portion of the chamber to which the latter faces are exposed, one of the latter faces adapted to close the opening with the plunger in the extreme

position toward which it is urged by the pressure acting against the first pressure face, a fitting for supplying pressure fluid to the pressure dome at a predetermined rate, and vent means for the dome and the portion of the chamber housing the two differential pressure faces operable with the plunger in extreme position urged by pressure acting against these differential faces, whereby when the force of pressure in the dome against the differential face exposed thereto is greater than the force due to pressure against the first pressure face the other differential pressure face will be energized, the additive force due to pressure acting against the two differential pressure faces positively driving the plunger to vented position from which it will be returned by the pressure operating against the first pressure face.

8. The motor of claim 7 wherein the fitting for pressurizing the dome is adjustable to vary the rate of flow of pressure fluid into the dome.

9. The motor of claim 7 wherein an adjustable stop extending into the chamber is engaged by a portion of the plunger to determine the length of power stroke.

10. The motor of claim 9 wherein the adjustment for the stop includes a heat sensitive element exposed exteriorly of the housing which is connected to the stop and is adapted to automatically adjust the stop to shorten the power stroke as the temperature of the medium to which the heat sensitive element is exposed increases.

11. The device of claim 7 wherein the fitting for pressurizing the dome includes a passage communicating between the dome and the portion of the chamber within which the first pressure responsive face resides.

12. A motor adapted to have an operating connection with a rod for reciprocating same intermittently at regular intervals comprising first and second cylinders mounted in substantial axial alignment, a pressure dome communicating with the second cylinder at its end remote from the first cylinder, fittings through which pressure fluid may be supplied to the pressure dome and the first cylinder, a plunger extending between and into the cylinders and mounted for axial reciprocation therein, a sliding seal between the plunger and the first cylinder sealing off a pressure face on the plunger exposed to the interior of the first cylinder whereby the pressure within the first cylinder urges the plunger toward the second, a pressure face carried by the plunger within the second cylinder and exposed to pressure fluid supplied thereto by the dome, a part carried by the plunger of lesser area than the pressure face, said part adapted to close the communication between the dome and second cylinder and be exposed to pressure within the dome with the plunger in its position just commencing its power stroke and vent means for relieving the pressure within the second cylinder and dome with the plunger in its other extreme position.

13. The motor of claim 12 wherein the fitting for supplying pressure to the dome is a passage

communicating between the interior of the first cylinder and the dome.

14. The motor of claim 12 wherein the fitting for pressurizing the dome is adjustable to vary the rate of flow of pressure fluid into the dome.

15. The motor of claim 12 wherein an adjustable stop extends into one of the cylinders and is engageable by a part of the plunger to determine the length of the power stroke.

16. A motor adaptable for connection to a rod for intermittently reciprocating the same, comprising a housing with a pressure chamber therein, a pressure responsive member in the chamber and connectable with a rod, means for intermittently pressurizing the chamber to drive the pressure responsive member in a power stroke comprising a pressure dome with a connection for supplying pressure thereto at a predetermined rate, a passage between the dome and pressure

chamber, and a part carried by the pressure responsive member and adapted to close the passage with the pressure responsive member in position to commence its power stroke and to be moved therefrom to start the pressure responsive member on its power stroke when the pressure within the dome reaches a predetermined value, the effective area of said part being less than the effective area of the pressure responsive member, means yieldingly urging said pressure responsive

member in a direction opposite its power stroke, and a vent for the pressure chamber when the pressure responsive member is at the end of the power stroke.

17. In a motor adapted for actuating a pump or the like, a housing, a pressure responsive member in the housing, said member providing interiorly of the housing a variable capacity pressure compartment, means including a vent, said

means actuated by movement of said pressure responsive member to vent said pressure compartment at the limit of the power stroke, a means yieldingly urging the pressure responsive member in a direction opposed to the power stroke, means for pressurizing the compartment at a predetermined rate, and a plunger connected to the pressure responsive member for reciprocation therewith and extending along the longitudinal axis of the housing and exteriorly of the housing.
